SHOWER BATH SPRAY HEAD

Robert C. Boyd, Louisville, Ky., assignor to Standard Sanitary Manufacturing Company, a corporation of New Jersey

Application June 30, 1934, Serial No. 733,253

11 Claims. (Cl. 299—144)

This invention relates to spray heads and more particularly to spray heads for shower baths where a tub is to be used as the shower receptor.

An object of this invention is to produce a spray head which, when used in conjunction with a bath tub, as a shower bath, will provide a multi-jet spray which covers an area conforming more or less to the shape and size of the opening of the tub which serves as the receptor for the shower.

Another object of this invention is to produce a shower bath spray head having a spray position and flushing positions and which is simple of construction and of relatively few parts.

15 A still further object of this invention is to produce a shower bath spray head which may be readily flushed for the removal of chips or loose sediment and which has a flow obstructing member which is readily removable and which 20 may have its jet forming grooves or notches readily cleaned by means of a brush.

A still further object of this invention is to produce a shower bath spray head which is readily cleanable, easily flushed and which is formed 25 to deliver two series of multiple jets arranged side by side and which is capable of being utilized in conjunction with a bath tub.

The objects above set forth I attain by means 30 of the device described in the specification and illustrated in the drawing accompanying and forming part of this application.

In the drawing, Figure 1 is a longitudinal sectional view of a casing (with the flow obstructing member in side elevation) of a shower bath 35 spray head embodying this invention.

Fig. 2 is a section taken on line II—II of Fig. 1 with the handle omitted.

Fig. 3 is a bottom plan view with a portion broken away of the device shown in Figs. 1 and 2.

40 Fig. 4 is a bottom view of the flow obstructing member of my device.

Fig. 5 is a top plan view of said flow obstructing member, and

Fig. 6 is a view similar to Fig. 2 of a modified 45 form of my invention.

The shower bath spray head illustrated in Figs. 1 to 5 inclusive comprises a casing or shell 7 provided with an inlet 8 which is interiorly threaded for connection to a water supply pipe. 50 The bottom or outlet end 9 of the casing is preferably rectangular and elongated and while in the form shown in the drawing, the casing is relatively heavy, it will be understood that the walls may be of the thickness used in ordinary shower heads and the contours may be changed

to suit the fittings with which the shower head is to be utilized.

The elongated portion of the casing which I will term the bottom of the casing (since this will be the bottom when the shower head is in position over a receptor), has two rectangular elongated outlet openings 10 and 11 located side by side and with their side walls all parallel. These openings are formed by extensions of the side walls of the casing and a centrally located 10 bar 12.

Spanning the casing and located a distance above bar 12 is a longitudinally extending bar 13. Extending inwardly from the side walls and positioned midway between bars 12 and 13 are opposed ledges 14 and 15, which extend the full length of the casing and in reality with the ends of the casing form the casing outlet.

One end of the rectangular portion of the casing is provided with a circular cored opening and 20 through this opening the adjacent faces of bars 12 and 13 and ledges 14 and 15 are bored or otherwise machined to receive the cylindrical ends 16 and 17 of a flow obstructing member 18.

The opening in the end of the casing through 25 which the tool is inserted for machining bars 12 and 13 and ledges 14 and 15 is threaded as shown at 19 to receive a follower nut 20. The threads are tapered as is usually done in plumbing fixtures and located in the bore inside of follower 30 nut 20 is a washer-like follower 21 and a pre-formed packing ring 22 of some yieldable material. The packing ring is confined between shoulder 23 adjacent one end of the flow obstructing member 18 and follower 21.

The outer end of the flow obstructing member adjacent the follower nut 20 is reduced in diameter as at 24, has a portion of its outer surface 25 knurled and is drilled and tapped to receive a retaining screw 26. An operating handle 27 provided with a serrated bore which snugly fits the serrated surface 25 is retained in position by retaining screw 26 and is prevented from turning independently of the flow obstructing member 45 because of the cooperating serrations.

The flow obstructing member throughout the major portion of its length has one side flattened as shown at 28 and the cylindrical surfaces on each side of the flattened portion are provided 50 with milled grooves or channels 29. As shown in Figs. 4 and 5, these may be of varying depths and preferably one half of the grooves of each series (those on one side of the member forming one series and those on the other another series) 55

discharges its jets at an angle to those of the other half. The grooves are so formed that the jets diverge slightly so that when the shower head is positioned at the proper height over a bath tub, the area covered by the spray delivered by the shower head will be slightly less than the opening of the tub.

By varying the angle of divergence of the grooves, it is possible to more or less fill with jets the area outlined by the spray.

Bar 13 is cast integrally with the shell proper and its function is to facilitate boring out of the cavity for the flow obstructing member 18.

While bar 12 has a similar function to bar 13, it has an added and important function, as will be hereinafter pointed out.

The end of flow obstructing member 18 opposite inlet 21 is cut away as shown at 30, Figs. 2, 3, and 4 and a stop 31 is provided at the inner end 20 of the bore for the flow obstructing member. This stop is preferably formed by driving a pin of the proper size through a hole (not shown) formed at the proper point in the end wall of the casing. The pin, after being driven in the proper distance, is preferably sweated in place. This stop, when follower nut 20 is in position, prevents complete rotation of the flow obstructing member 18 (because of the shoulder formed by the cut away portion 30) and limits the movement of the flow obstructing member to a back and forth oscillation.

When the flow obstructing member is in operative position its cylindrical surface will be down and handle 27 will be in down position as shown in Fig. 1 so that the jets are defined by the grooves 29 and the curved walls of ledges 14 and 15. With the parts in this position, the two series of jets will discharge a spray of more or less rectangular outline and the two series will discharge the streams or jets more or less parallel, one series to the other, although one half the jets of each series will slightly diverge from those of the other half.

By turning the handle to one side or the other, 45 a flushing opening 32 is provided alongside of the flow obstructing member. This is clearly shown in Fig. 3. By turning the handle to the other side, a corresponding opening will be provided on the opposite side of the flow obstructing member. By thus manipulating the handle, chips or loose 50 sediment or other dirt which has collected in the shower head may be readily discharged.

By loosening follower nut 20 without removing the handle 27 the flow obstructing member may 55 be removed from its bore and any sediment or deposit which has collected in grooves 29 may be cleaned therefrom by means of a brush. Since a preformed packing is utilized, the different parts of the flow obstructing device may be removed as a unit and may also be replaced as a unit. This provides a ready way of removing 60 deposits such as lime deposits which always collect in shower head spray openings.

If the flow obstructing member is oscillated 65 with the water pressure on, the series of jets on one side or the other as the case may be, will have a tendency to "walk" laterally of the device and if walls 33 and 34 were not extended below the ledges 14 and 15 and if bar 12 were not positioned below the flow obstructing member, then 70 walking of the series of jets would cause the spray to discharge outside of the tub over which the shower head is located. By means of these extended walls 33 and 34 and bar or bridge member 12, the "walking" jets are intercepted; the

jets are broken up and the water will fall in the form of drops into the receptacle.

The arrangement is such that the flow obstructing member is in operative position when the handle is turned straight down. There is 5 intended to be no adjustment of the spray head, but it is supposed to be either in operative position or in one or the other of its flushing positions.

In the form shown in Fig. 6, the grooves instead of being formed in the flow obstructing member are formed in the adjacent faces of inwardly extending ledges 14a and 15a.

The flow obstructing member, while it is cylindrical on its ends throughout its major portion 15 is somewhat less than half a cylinder as shown at 18a.

The grooves in the ledges 14a and 15a may be positioned at different angles so as to properly direct the individual jets forming the spray. 20

A follower nut with a preformed packing and follower and the same type of a handle may be used as shown in the other form in Figs. 1-5 inclusive and when it is desired to clean the grooves in ledges 14a and 15a the flow obstructing member may be removed and the grooves may be cleaned by means of a brush, as will be readily apparent. A thin, flat brush may be inserted within the space usually occupied by the flow obstructing member and by moving the 30 same back and forth or up and down, it will be seen that the grooves may be readily cleaned of any deposits.

Having thus described my invention, what I claim as new and desire to secure by Letters 35 Patent is:—

1. A shower bath spray head comprising a shell or casing having a water inlet and an elongated rectangular water outlet, a flow obstructing member mounted for oscillation within said casing over the outlet and provided with two rows 40 of jet forming grooves.

2. A shower bath spray head comprising a shell or casing having a water inlet and an elongated water outlet, a flow obstructing member mounted 45 for oscillation within said casing between the inlet and outlet and provided with two rows of jet forming grooves.

3. A shower bath spray head comprising a shell or casing having a water inlet and an elongated 50 rectangular water outlet, a flow obstructing member mounted for oscillation within said casing between the inlet and outlet thereof and having grooves in opposite sides which cooperate with the walls of said outlet in providing two spaced 55 rows of water jets.

4. A shower bath spray head comprising a shell or casing having a water inlet and an elongated water outlet, a flow obstructing member mounted 60 for oscillation within said casing between the inlet and outlet and having grooves in opposite sides which cooperate with the walls of said outlet in providing two spaced rows of water jets.

5. A shower bath spray head comprising a shell or casing having a water inlet formed for attachment with a water supply pipe, an elongated parallel sided water outlet, a flow obstructing member mounted for oscillation within said outlet and having its surface located toward the interior of the casing flattened and its other surface formed as part of a cylinder, a series of grooves on opposite sides of the flow obstructing member and extending from said flattened portion into said cylindrical portion and with the walls of said outlet constituting jet openings, 75

baffle members located on the outlet side of said water outlet; one located on each side of said water outlet, and one at the center thereof and means for oscillating said flow obstructing member.

5. A shower bath spray head comprising a shell or casing having a water inlet formed for attachment with a water supply pipe, an elongated parallel sided water outlet, a flow obstructing member mounted for oscillation within said outlet and having its surface located toward the interior of the casing flattened and its other surface formed as part of a cylinder, and a series of grooves on opposite sides of the flow obstructing member and extending from said flattened portion into said cylindrical portion and with the walls of said outlet constituting jet openings.

6. A shower bath spray head comprising a casing having a water inlet, a substantially rectangular water outlet, a flow obstructing member controlling said outlet and provided with two spaced rows of grooves which cooperate with the walls of said outlet to provide two rows of water jets; said flow obstructing member being formed in the nature of a cylinder with one side flattened; said grooves being formed in the cylindrical portion thereof; the flattened side of said member when said member is in operative position facing toward the interior of said casing; said member 30 being capable of being oscillated so that said flattened side provides channels for flushing the device.

7. A shower bath spray head comprising a casing having a water inlet and an elongated generally rectangular water outlet, an elongated flow obstructing member mounted for oscillation with-

in said casing between the water inlet and outlet, a row of spray jets on each side of said member and formed by cooperation between said member and the walls of said outlet.

9. A shower bath spray head comprising a shell or casing having a water inlet and an elongated water outlet, shoulders projecting inwardly from opposite sides of said casing between the water inlet and outlet ends thereof, a flow obstructing member mounted for oscillation between the shoulders of said casing and cooperating therewith when in one position to provide two spaced spray openings.

10. A shower bath spray head comprising a shell or casing having a water inlet and an elongated rectangular water outlet, internal walls extending longitudinally of said casing between the water inlet and outlet ends thereof, and a flow obstructing member mounted for oscillation in said casing between said walls, the said member 20 being of general cylindrical shape and cooperates with said walls to provide two spaced spray openings therebetween.

11. A shower bath spray head comprising a shell or casing having a water inlet and an elongated generally rectangular water outlet, internal walls on opposite sides of said casing extending lengthwise thereof between its water inlet and outlet ends and a generally cylindrical flow obstructing member mounted for oscillation between the ends of said internal walls, said member having a flattened side to provide, when in one position, two spaced spray openings and when in another position a relatively wide flushing opening adjacent one wall.
